UNITED STATES PATENT OFFICE

ERVIN G. SHEDRICK, OF MANCHESTER, PENNSYLVANIA

SHEET LATHING

Application filed October 27, 1928. Serial No. 315,471.

This invention relates to lathing, and more particularly to sheet lathing adapted to be shipped and sold in rolled form.

An important object of the invention is to provide a novel form of sheet lathing having outstanding projections adapted to interlock with the plaster or other material, the body of the lathing, aside from the projections referred to, being substantially continuous to produce an article of material strength and one which readily may be applied.

A further object is to provide a lathing of the character referred to which is adapted to be cheaply manufactured of light readily handled material, and which possesses a material degree of strength to properly reinforce the plaster or other material applied thereto.

20 A further object is to provide a sheet lathing of the character referred to which has projections formed on the outer face thereof for engagement with the plaster or other material, the projections acting as gages to permit the plaster to be uniformly applied, and as means for reinforcing the sheet to render it substantially rigid.

A further object is to provide a sheet lathing having projections of the character referred to, and being further provided with punched out portions forming pockets adapted to receive the plaster whereby the latter may be tightly interlocked with the lathing.

25 A further object is to provide a lathing of the character referred to which possesses a material degree of flexibility in one direction to permit it to be manufactured in relatively long sheets and to be rolled to facilitate handling and shipment.

30 A further object is to provide a lathing which is flexible in one direction for the purpose referred to and substantially inflexible in the opposite direction to facilitate the stretching thereof into a flat plane and thus facilitate its proper application to the studing or other supports to which it is to be attached.

A further object is to provide a composite lathing formed of a pair of superimposed sheets one of which is provided with means

on its outer face adapted to interlock with the plaster, while the other sheet is adapted to prevent the passage of moisture through the lathing.

35 A further object is to provide a sheet lathing made up of a sheet of metal and a backing sheet of waterproof material, the metal sheet being provided with punched out portions forming pockets to receive plaster or similar material whereby the latter will interlock with the metal sheet, the waterproof material forming a closure for the pockets and preventing the passage of moisture through the lathing.

40 A further object is to provide a sheet lathing of the character referred to which is flexible and is adapted to receive plaster or similar material applied to the outside face thereof, such outside face being provided with ribs adapted to reinforce the lathing and to interlock with the plaster, and being adapted to serve the additional function of reinforcing the corner portion of a plaster wall to prevent injury to the plaster at that point.

45 Other objects and advantages of the invention will become apparent during the course of the following description.

In the drawings I have shown several embodiments of the invention. In this showing,

50 Figure 1 is a face view of a portion of a sheet of lathing,

Figure 2 is a vertical sectional view through the same showing the plaster applied,

55 Figure 3 is a fragmentary perspective view showing the rear face of the lathing, and,

Figure 4 is a detail sectional view of a modified form of lathing.

60 Referring to Figures 1, 2 and 3, the numeral 10 designates a sheet forming the body of the lathing, and preferably made of light gauge sheet. The body of the lathing is provided with preferably parallel outstanding ribs 11, the sides of which preferably contact with each other whereby the body of the sheet 10 is substantially continuous. The ribs 11 are preferably inclined with respect to the body of the sheet 10, as clearly indicated in Figure 2.

65 The sheet 10 is provided between the ribs 11 with punched out portions 12 which form

95

95

100

pockets 13 for the reception of plaster or similar material applied against the face of the sheet. It will be apparent that the metal forming the punched out portions is substantially conical in shape and thus the pockets 13 decrease in size outwardly of the face of the sheet 10, thus forming an efficient means for interlocking the sheet and plaster together. In Figure 2 of the drawings, a layer of plaster or similar material 14 is shown applied against the face of the sheet. It will be apparent that the plaster is interlocked with the ribs 11 and the punched out portions 12 of the sheet, the plaster, when applied, being forced into the pockets 13 as shown in Figure 2.

A sheet of waterproofed material 15 is arranged against the back of the sheet 10. This material may be formed of paper impregnated with waterproofing material such as tar, pitch, creosote or the like, and the waterproofing sheet is preferably secured against the sheet 10 by a layer of adhesive 16. It has been found that the paper or other waterproofed backing may be secured to the sheet 10 to form a composite sheet which is substantially rigid longitudinally of the ribs 11, but which possesses a substantial degree of flexibility transversely of the ribs whereby the sheet may be rolled in the latter direction without loosening the backing 15 from the body of the sheet. Thus it will be apparent that the finished lathing may be shipped in rolled form, and readily may be unrolled to permit it to be arranged flat against the studing or other supports.

The ends of the ribs 11 adjacent one end of the sheet are preferably cut transversely as at 17, and the portions of the ribs 18 lying between the cuts 17 and the adjacent ends of the sheet are rolled downwardly flat against the body of the sheet whereby the sheets are adapted to be overlapped when placed in position to eliminate the cracking of the plaster at the joints between the sheets of lathing.

The body of the lathing shown in Figure 4 is identical with that previously described and need not be referred to in detail. In the modified form of lathing, a sheet of material 19 is employed which is heavily impregnated with waterproofing material of an adhesive nature. For example, heavily tarred paper may be employed, and the paper may be caused to adhere directly to the metal sheet by applying it thereto with heat and pressure.

The operation of the lathing is as follows:

The sheet 10 is adapted to be manufactured with an apparatus similar to that disclosed in my copending application Serial No. 271,556, filed April 20th, 1928. The ribs 11 and punched out portions 12 are formed in the body of the sheet, and as previously stated, the sides of the ribs preferably lie against each other whereby the body of the sheet 10 is substantially continuous and unbroken. It

has been found that the body 10 may be manufactured from very light sheet metal, and when placed in position to be plastered, it possesses a substantial degree of rigidity to properly reinforce the plaster.

The placing of the backing 11 against the sheet in the manner referred to serves to waterproof the lathing, thus preventing the plaster from absorbing moisture through the lathing. The backing also serves to close the pockets 13 to prevent the plaster from being wasted by being forced from the opposite side of the sheet through the pockets 13. It will be apparent that as the plaster is applied against the sheet, the contact of the plaster with the sheet 15 causes the plaster to spread transversely to fill the pockets 13 and thus become firmly interlocked with the sheet.

The lathing may be applied with the ribs horizontally arranged as shown in Figures 1 and 2, or the ribs may be vertically arranged if desired. When the ribs are arranged horizontally and the sheet is applied to vertical studding, the studding reinforces the sheet vertically while the ribs 11 render the sheet rigid horizontally. It is the present practice to reinforce the corners of plastered walls with metal inserts embedded into the plaster and having edge portions flush therewith to prevent the corners of the plaster from being chipped off. The flexibility of the sheet forming the subject matter of the present invention is such that at the corners of walls, the ribs may be arranged vertically with one rib coinciding with the corner, whereupon the sheet may be bent and the rib 11 at the corner of the wall will act as a metal reinforcing element to prevent the plaster at the corner of the wall from being chipped off.

The ribs 11 are identical, and each has its edge portion arranged parallel to the body of the sheet 10. Thus the ribs are adapted to act as thickness gages to permit the plaster to be uniformly applied against the sheet. The end portions 18 of the ribs are rolled flat against the body of the sheet to permit overlapping of the sheets, and thus cracking of the plaster between the sheets will be eliminated.

In operation, the form of the lathing shown in Figure 4 is identical with that previously described, this form of the invention merely being provided with an adhesive backing sheet instead of having a layer of adhesive applied between the sheets. A sheet of lathing constructed in accordance with either form of the invention readily may be rolled transversely of the ribs 11, the rolling action taking place without injury to the ribs 11 or punched out portions 12, and without causing any separation between the metal sheet and the backing sheet. Thus handling and shipment of the lathing is greatly facilitated.

As previously stated, the sheet 10 is preferably made of very light gage sheet metal,

and the finished sheets of lathing are thus light and easily handled. It also will be apparent that an ordinary pair of tin snips may be employed for cutting the sheets wherever necessary, and accordingly the application of the lathing is greatly facilitated.

It will be apparent that the backing of water-proof material protects the metal sheet against the action of moisture, and accordingly the deterioration of the metal sheet by rusting is prevented. It also will be apparent that the provision of the backing sheet prevents the wasting of mortar which otherwise would occur through the forcing of excess mortar through the apertures in the metal sheet. The backing sheet serves the additional function of deadening the metal sheet against vibration, thus assisting in providing a sound proof wall. It also will be noted that the waterproof sheet acts as an insulating covering for the metal thus tending to avoid radio disturbances. The invention thus includes all of the essential characteristics of a perfect lathing structure.

It is to be understood that the forms of the invention herewith shown and described are to be taken as preferred examples of the same and that various changes in the shape, size and arrangement of parts may be restorted to without departing from the spirit of the invention or the scope of the subjoined claims.

I claim:—

1. A sheet of lathing comprising a normally flat imperforate layer of waterproof material and a coextensive perforate sheet attached thereto by adhesion, said perforate sheet having portions adapted to be embedded in a layer of plastic material applied thereto.

2. A sheet of lathing comprising a normally flat imperforate layer of waterproof material, and a second layer of material coextensive therewith and applied thereto and provided with punched out openings forming projections adapted to be embedded in a layer of plastic material applied against said second layer of material.

3. A sheet of lathing comprising a normally flat imperforate layer of waterproof material, and a second layer of material coextensive therewith and applied thereto and provided with punched out portions forming with said waterproof material a plurality of pockets adapted to receive some of a layer of plastic material applied to said second layer of material.

4. A sheet of lathing comprising a relatively large sheet of material having punched out portions extending from one side thereof forming openings therein, and a layer of material coextensive with and fixed against the opposite side of said sheet of material, said layer of material being normally flat and imperforate and forming with said openings a plurality of pockets adapted to receive some

of a layer of plastic material applied against said sheet of material.

5. A sheet of lathing comprising a sheet of relatively thin sheet metal formed with a plurality of longitudinal ribs having their sides extending from one side thereof, each of said ribs substantially contacting with each other whereby the body of said sheet of metal is substantially continuous and unbroken, said sheet of metal being provided with punched out portions forming openings between said ribs, and a normally flat layer of imperforate waterproof material coextensive with and fixed against the opposite side of said sheet of metal.

In testimony whereof I affix my signature.
ERVIN G. SHEDRICK.
